UNITED STATES PATENT OFFICE.

PAUL GAUTHIER, OF COURBEVOIE, FRANCE.

AUTOMATIC LIFTING WINDLASS.

Application filed June 21, 1924. Serial No. 721,538.

To all whom it may concern:

Be it known that I, PAUL GAUTHIER, a citizen of the Republic of France, residing at Courbevoie, Seine, France, have invented 5 certain new and useful Improvements in Automatic Lifting Windlasses, of which the following is a specification.

This invention relates to automatic lifting devices or windlasses, the characteristic features of which are:

1. The clutch is thrown into operation automatically on the ascent of the load and on its descent by means of a single lever.

2. The clutch is thrown out of operation automatically on the ascent or descent of the load, or during one of these two motions only, after a fixed travel or stroke, and a safety device is provided to prevent the clutch from being thrown into operation for 20 the ascent or descent of the load as the case may be.

3. The automatic throwing out of action of the clutch on the descent of the load when the latter encounters any kind of 25 obstacle which reduces the tension of the cable below a given point.

4. The automatic return of the cable to its uppermost position on being freed from its load.

5. A safety device which prevents the cable being operated without operating the lever and which, when the windlass is mounted on a truck, prevents operation of 30 the cable while the vehicle is in motion.

35 The accompanying drawings show what is now regarded as the preferred embodiment of this invention; Figure 1 being a plan view of the mechanism and Fig. 2 a side elevation thereof, the casing being 40 shown in section in both figures, while Figs. 3 and 4 are detail views of the operating worm and the drum.

The windlass according to this invention is chiefly composed of a casing 1 closed by 45 a lid or cover (not shown) and having journaled in it a horizontal shaft 2^a to which is fixed a drum 2 whereon the cable 3 is wound.

The drum 2 carries on its exterior a toothed wheel or worm gear 4 meshing with 50 an endless screw or worm 5 capable of being shifted in a lateral direction along a shaft 6 perpendicular to the drum shaft 2^a. The drum shaft is provided with toothed pinion 7 meshing with a gear 8, the shaft

9 of which is fixed to the casing 1, said gear 55 carrying adjacent its periphery a projection 10. The shaft 6 extends upwardly through a sleeve 11, the lower end 11' of which forms a stop to limit the movement of the worm 5 in one direction; movement thereof in 60 the opposite direction being limited by the bottom wall of the casing 1.

On the upper part of the sleeve 11 are fastened spaced upper and lower gears 34 and 33 which mesh, respectively, with two 65 other gears 36 and 35 loosely mounted on a shaft 37. The latter gears have clutch teeth formed on their confronting inner faces for alternative engagement by an intermediate clutch sleeve 12 which is toothed 70 at opposite ends, as shown, and is adapted to be moved in either direction along shaft 37 by a shifting lever or yoke 13 actuated by the rod 15 that sets the windlass in motion; the supporting shaft or pivot 14 of 75 the yoke being mounted in a bearing 14' rigidly secured to the casing. The clutch sleeve 12 is keyed to shaft 37 which latter may be rotated in any desired manner; the construction illustrated embodying a drive 80 shaft 16 and a transmission connection comprising toothed wheels 17 and 18 or the like.

At a suitable point on the cover (not shown) of the casing, there is mounted a stud or pivot 20 whereon is centrally fulcrumed a lever 19 having a link 19' pivot- 85 ed to one end thereof; the other end of the lever being formed with an eye 21' to receive the knuckle 21 provided on the adjacent end of a second lever 22 which is 90 fulcrumed on a stud 23 fixed to the casing. The foot 24 of lever 22 is adapted to be operatively engaged at the proper times by the finger or projection 10 on gear 8. A stirrup 25, also fixed to the casing, 95 holds the worm 5 in its inoperative position (in which it is disconnected from worm wheel 4) after the descent of the load when the direction of rotation of the reversing mechanism does not correspond to the ascent of the load.

Within the interior of the drum 2 is arranged a return spring 26, one end of which is fastened to a member 27 secured to the casing while its other end is fastened at 28 105 to the drum hub; the arrangement of this spring being such that its tension is exerted during the downward movement of the

load. Finally, a spring 29 wound around the shaft 6, constantly presses the worm 5 against stirrup 25 so that when the movement of rotation corresponding to the ascent of the load takes place, the worm is forced to move toward wheel 4, whereas in the other direction of rotation it merely turns idly.

The operation is substantially as follows: 10 By moving the rod 15 into the position corresponding to ascent, the yoke 13 is shifted to engage the clutch sleeve 12 with the proper gear which, in this instance, is the upper gear 36, the consequent rotation of 15 which is transmitted to shaft 6 with the result that the engagement of the threads of worm 5 with stirrup 25 causes said worm to move in the direction indicated by the arrow 30 (i. e. upward). The worm is thereby engaged with worm wheel 4, continues its movement until it reaches stop 11' and at that moment commences to rotate drum 2 which thus effects the ascent of the load. As the drum turns, its pinion 7 rotates gear 8, 25 and the finger 10 on said gear is caused to strike against the foot 24 of lever 22 after a predetermined length of cable has been wound up which can be regulated as will be apparent. This contact of finger 10 with 30 lever 22 serves to rock the latter, such rocking movement being transmitted to lever 19 and thence to link 19', whereby yoke 13 and clutch sleeve 12 are brought back to neutral position, said sleeve thus being disengaged 35 from gear 36 and the hoisting of the load terminated. No mistake in the working of the windlass can occur, as the position of finger 10 prevents the rod 15 from being operated again in the direction for hoisting, 40 so that the load is thus held at this moment by the non-reversibility of the worm 5.

To unship a load, the rod 15 is moved in the direction for descent and the yoke 13 then brings clutch sleeve 12 into engagement with gear 35, whereby shaft 6 and worm 5 are caused to rotate in the opposite direction from that previously described. The tension of cable 3 holds worm 5 against stop 11', however, and causes it to actuate 45 worm wheel 4 and drum 2 to drop the load; and since the direction of rotation of said drum is the reverse of its former rotation, the gear 8 will likewise be reversed and finger 10 will move away from the lever foot 50 24. As soon as the tension of the cable diminishes and falls below a predetermined limit, the worm will no longer be held against stop 11' by wheel 4 but will be caused to move downward along shaft 6, being guided in its movement by said wheel 55 which is stationary and actionless at that time, and passes over stirrup 25 which holds it against the casing 1 so long as the clutch sleeve 12 rotates in the direction of descent 60 or is stopped. Stoppage may, however, be 65

effected in any other way as, for example (1) by hand at any point whatsoever, merely by moving rod 15 in a direction to cause yoke 13 to shift clutch sleeve 12 into neutral position, or (2) automatically after 70 a predetermined movement of finger 10 which, on having substantially completed one revolution with gear 8, acts as it does on the ascent of the load and forms a safety device which precludes all mistakes in working when the load descends. 75

After the load has been unshipped, the spring 26, which has been tensioned during the descent of the load, automatically returns the cable to its upper position, the 80 drum 2 being at this moment disconnected from the operating worm. The cable can then be brought back to its lower position by hand, during which action the said spring is tensioned; and in order to prevent 85 finger 10 from operating the clutch sleeve in the reverse direction when the cable is unwound to the predetermined limit, and thus causing it to be immediately wound up again, a stop 31 fixed to the casing 1 is 90 caused to be engaged by a second finger 32 on gear 8, whereby the said gear is held against movement. 95

When the windlass is used on a truck, means may be provided for preventing the 95 operation of the windlass even if the starting rod 15 be actuated.

While the preferred embodiment of the invention has been illustrated and described, it is to be understood that no limitative action is imposed thereby excepting as 100 may be determined by the scope of the appended claims.

I claim as my invention:

1. A windlass, comprising a winding 105 drum, a drive shaft, a worm gear for rotating said drum slidably axially on said shaft and rotating therewith, means for limiting the sliding movement of the worm in both directions, a clutch device for controlling the direction of rotation of the drive shaft and including a movable clutch sleeve, and an operating element for shifting said sleeve in either direction. 110

2. A windlass, comprising a winding 115 drum, a drive shaft, a worm gear for rotating said drum slidably axially on said shaft and rotating therewith, means for limiting the sliding movement of the worm in both directions, a clutch device for controlling the direction of rotation of the drive shaft and including a movable clutch sleeve, an operating element for shifting said sleeve in either direction, a fixed element with which the worm is engaged at a 120 predetermined point in its movement on the shaft, and a spring for moving said worm in one direction. 125

3. A windlass, comprising a winding 130 drum, a drive shaft, a worm gear for rotat-

ing said drum slidable axially on said shaft and rotating therewith, means for limiting the sliding movement of the worm in both directions, a clutch device for controlling 5 the direction of rotation of the drive shaft and including a movable clutch sleeve, an operating element for shifting said sleeve in either direction, a worm wheel fixed to said drum to rotate therewith and immediately engaged by the worm, and a spring 10 engaged with said drum to return the same and the worm wheel to normal position and to hold the worm in its upper position.

4. A windlass, comprising a winding 15 drum, a drive shaft, a worm gear for rotating said drum slidable axially on said shaft and rotating therewith, means for limiting the sliding movement of the worm in both directions, a clutch device for controlling 20 the direction of rotation of the drive shaft and including a movable clutch sleeve, an operating element for shifting said sleeve in either direction, a worm wheel fixed to said drum to rotate therewith and immediately engaged by the worm, a spring 25 engaged with said drum to return the same and the worm wheel to normal position and to hold the worm in its upper position, a fixed element with which the worm is engaged at a predetermined point in its move- 30

ment on the shaft, and a spring for moving said worm in one direction.

5. A windlass, comprising a winding drum, a drive shaft, a worm gear for rotating said drum slidable axially on said shaft, 35 a clutch device for controlling the direction of rotation of the drive shaft and including a shiftable clutch sleeve, a clutch shifter engaging said sleeve, and means actuated by the rotation of the drum for automatically operating the clutch shifter to move the clutch sleeve to neutral position.

6. A windlass, according to claim 5, in which the automatic operating means comprise a pinion driven by the drum and provided within a projection, a rocker adapted 45 to be engaged and actuated by said projection, and a connection between the rocker and the clutch shifter.

7. A windlass, comprising a winding 50 drum, a drive shaft, means carried by said shaft for rotating the drum, a gear driven by said drum and provided with a projection, and a fixed stop cooperative with said projection to arrest the rotation of said 55 gear.

In testimony whereof I affix my signature.

PAUL GAUTHIER.
